U.S. Appl. No. 29/765,915, filed Jan. 12, 2021, Jinsheng Lu.
(Continued)

Primary Examiner — Elizabeth A. Albert

(74) Attorney, Agent, or Firm — Marc A. Hubbard;
Hubbard Law, PLLC(57) **CLAIM**

The ornamental design for a desktop organizer, as shown and described.

DESCRIPTION

FIG. 1 is a front perspective view of a desktop organizer; FIG. 2 is a front elevation view thereof; FIG. 3 is a rear elevation view thereof; FIG. 4 is a top view thereof; FIG. 5 is a bottom view thereof; FIG. 6 is a right side view thereof; and, FIG. 7 is a left side view thereof.

The broken lines show portions of the desktop organizer that form no part of the claimed design.

The broken away symbols in the drawings indicate that the appearance of any portion of the article between the break lines forms no part of the claimed design.

1 Claim, 7 Drawing Sheets
